US0D1096819S

(12) **United States Design Patent** (10) Patent No.: **US D1,096,819 S**
(45) Date of Patent: ** Oct. 7, 2025

(54) **DISPLAY SCREEN WITH GRAPHICAL USER INTERFACE**

(71) Applicant: **Biosense Webster (Israel) Ltd.**, Yokneam (IL)

(72) Inventors: **Yevgeny Bonyak**, Yokneam (IL); **Michael Levin**, Haifa (IL); **Eyal Rotman**, Haifa (IL)

(73) Assignee: **Biosense Webster (Israel) Ltd.**, Yokneam (IL)

(**) Term: **15 Years**

(21) Appl. No.: **29/759,151**

(22) Filed: **Nov. 20, 2020**

Related U.S. Application Data

(63) Continuation-in-part of application No. 16/726,045, filed on Dec. 23, 2019, now Pat. No. 11,006,902.

Primary Examiner — Ian F Whitmore

(57)

CLAIM

The ornamental design for a display screen with graphical user interface, as shown and described.

DESCRIPTION

The sole FIGURE is a front view of the display screen with graphical user interface.

The broken lines in the drawing form no part of the claimed design. The outermost broken-line illustrates the perimeter of a display screen. The remaining broken lines illustrate portions of the graphical user interface.

1 Claim, 1 Drawing Sheet
